UNITED STATES PATENT OFFICE

2,110,690

ELECTRIC CIRCUIT INTERRUPTER

Georg Zierahn, Berlin, Germany, assignor to
 General Electric Company, a corporation of
 New York

Application February 20, 1936, Serial No. 64,959
 In Germany March 15, 1935

6 Claims. (Cl. 176—38)

My invention relates to electric circuit interrupters and more particularly to an interrupter adapted to be used with devices having a positive temperature-resistance coefficient, such as tungsten lamps.

According to my invention, the interrupter comprises a resistance element having a negative temperature-resistance coefficient and being electrically connected in series with the operating device, such as the filament of an incandescent lamp, and a thermal switch which is electrically connected in multiple with the said resistance element and is heated by it. One of the advantages of such a resistance element is that when the circuit is closed a small current flows through the filament of the lamp and heats it so that it glows but slightly or not at all. Then when the said resistance element becomes heated and closes the thermal switch the full line voltage is impressed across the filament so that it glows brightly. Thus the usual surge of current which occurs when the circuit is closed is prevented from passing through the filament by the resistance element. This is of great importance for example in the case of large incandescent lamps and particularly when several devices are connected in series which have different values of power consumption and heating time.

Further features and advantages of my invention will appear from the following detailed description of species thereof.

In the drawing, Fig. 1 is an elevation of an interrupter comprising my invention connected to an incandescent lamp, and Fig. 2 is an elevation of an incandescent lamp having an interrupter of modified form mounted in the bulb of the lamp.

Referring to Fig. 1, the interrupter 10 comprises a bulb 11 which may be similar to an incandescent lamp bulb. A resistance element 12 is mounted in said bulb 11 on a pair of conductors 13, 14. The said resistance element 12 preferably consists of an oxide which is conductive at ordinary room temperatures and has a high negative temperature-resistance coefficient, such as a body of uranium dioxide. A thermal switch 15, which may consist of a bimetallic strip, is also connected across the conductors 13, 14 in multiple with the resistance element 12 and is disposed adjacent to said resistance element so as to be heated thereby. The said resistance element 12 is connected in series with the filament 16 of an incandescent lamp 17 by a conductor 18. The said filament 16 is preferably of tungsten, which has a positive temperature-resistance coefficient.

The lamp and interrupter are connected to the line at 19 and 20.

The operation of the device is as follows:

When the circuit is closed, a small current first flows through the resistance element 12 and filament 16 which heats the filament at most to a dark red glow. When the resistance element 12 becomes warm as a result of the current flowing therethrough, it heats the switch 15 and causes it to close. The filament 16 is then connected across the full line voltage and it glows brightly. The resistance element 12 and switch 15 then cool down until the said switch is opened to again connect the said resistance element in series with filament 16 which glows but slightly as a result of the reduced current.

In the device shown in Fig. 2, the interrupter and filament are mounted in the same bulb 21. The thermal switch 22 in this case consists of a mercury switch mounted within a tubular resistance element 23 of the same type as the resistance element 12 in Fig. 1. The switch 22 is protected from the radiation of the filament 16 by a disc 24 which may be of mica. The electrical connections and operation of this device are the same as that shown in Fig. 1.

The use of a resistance element of semi-conducting material such as uranium dioxide has the advantage that it may be made quite small. Moreover, its resistance drops to such an extent during the heating that no great surge of current occurs at the consuming device, or filament, when the resistance element is short-circuited.

What I claim as new and desire to secure by Letters Patent of the United States is:

1. A circuit interrupter comprising a bulb containing a resistance having a negative temperature-resistance coefficient and a thermal switch electrically connected in multiple with said resistance and disposed adjacent to said resistance so as to be heated thereby.

2. A circuit interrupter comprising a bulb containing a tubular resistance body having a negative temperature-resistance coefficient and a thermal switch electrically connected in multiple with said resistance and disposed within said resistance body so as to be heated thereby.

3. A circuit interrupter comprising a bulb containing a tubular resistance body having a negative temperature-resistance coefficient and a mercury switch electrically connected in multiple with said resistance and disposed within said resistance body so as to be heated thereby.

4. A circuit interrupter comprising a bulb con-

taining a resistance body of an oxide which is conductive at ordinary temperatures and has a high negative temperature-resistance coefficient and a thermal switch electrically connected in 5 multiple with said resistance body and disposed adjacent to said resistance body so as to be heated thereby.

5. In a device of the type described, a circuit interrupter comprising a bulb containing a resistance element having a negative temperature-resistance coefficient and a thermal switch electrically connected in multiple with said resistance element and disposed adjacent to said resistance element so as to be heated thereby, and a filament 10 having a positive temperature-resistance coefficient and disposed adjacent to said resistance element so as to be heated thereby.

15 cient and electrically connected in series with said resistance element.

6. In a device of the type described, the combination of a bulb, a resistance element in said bulb having a negative temperature-resistance coefficient, a thermal switch in said bulb electrically connected in multiple with said resistance element and disposed adjacent to said resistance element so as to be heated thereby and a filament in said bulb having a positive temperature-resistance coefficient and electrically connected in series with said resistance element, said switch being spaced away from said filament so as to be unaffected in its operation by the heat radiation therefrom.

GEORG ZIERAHN.
